UNITED STATES PATENT OFFICE.

MICHAEL G. BLICK, OF CHICAGO, ILLINOIS.

TRENCH-DIGGER.

1,080,250.

Specification of Letters Patent.

Patented Dec. 2, 1913.

Application filed March 24, 1913. Serial No. 756,374.

To all whom it may concern:

Be it known that I, MICHAEL G. BLICK, a citizen of the United States, residing at Chicago, in the county of Cook and State 5 of Illinois, have invented certain new and useful Improvements in Trench-Diggers, of which the following is a full, clear, concise, and exact description, reference being had to the accompanying drawings, forming a part 10 of this specification.

My invention relates to trench diggers and contemplates certain improved features which go to make a simple, economical, durable and efficient machine.

Like some other trench diggers heretofore provided, the device of my invention comprises a vehicle structure which carries a series of digging shovels mounted upon an endless chain, said buckets emptying into a 20 suitable conveyer employed to carry the material discharged from the shovels to any desired point. The vehicle may if desired carry a power plant for manipulating the digging devices and also adaptable for traction purposes. The present invention, however, is not particularly concerned with any 25 particular form of vehicle so the said vehicle and some of the parts carried thereby are here shown more or less diagrammatically.

The present invention is particularly concerned with the provision of a digger frame pivotally supported by the vehicle structure, which digger frame is provided with suitable 35 sprocket wheels designed to engage the chain carrying the digging shovels. This digger frame, which must of necessity be of great strength, should preferably be expandable in order to meet varying conditions.

The digger frame of my invention comprises a hollow member, one end of which is pivotally connected to the vehicle structure. Projecting from the other end of said hollow member is a beam carrying a 40 sprocket wheel or sprocket wheels adapted to engage the chain carrying the digging shovels. This beam is adjusted relatively to the hollow member by rotating a shaft disposed within the hollow member, which shaft is 45 provided with a male thread engaging a female thread with which the beam is provided. The said male threaded shaft is preferably rotated by means of a worm and gear arrangement in order to secure the mechanical advantage necessary because of the 55 weight of the several parts. The hollow

member is preferably provided with rollers which serve to guide the beam and overcome friction.

My invention is set forth in more detail 60 in the following description, and is illustrated in the accompanying drawings, in which;

Figure 1 is a side elevational view illustrating a trench digger embodying my invention. The vehicle structure is here shown diagrammatically. Fig. 2 is a fragmentary sectional view taken on the line 2—2 of Fig. 1, and looking in the direction indicated by the arrows. Fig. 3 is a detail view illustrating the digger frame and parts associated therewith, the digger frame being shown partly in section and partly in elevation; and Fig. 4 is a plan view of the digger frame and the sprocket wheels carried 75 thereby.

Similar reference numerals refer to similar parts throughout the several views.

As illustrated in Fig. 1, the trench digger of my invention may if desired comprise 80 traction wheels 5 and a vehicle frame 6. Mounted upon the frame 6 is an upright 7 of any suitable material and conformation. Pivoted to the upright 7 is an arm 8 comprising side members and connecting brace 85 rods as illustrated. Pivoted to the vehicle frame at 9 are parallel racks 10 which are engaged by sprockets 11 mounted upon a shaft 12 bearing in the side members of the arm 8. Mounted upon the shaft 12 is a 90 drum 13 around which are wound cables 14 which pass over a roller 15 carried by the top of the upright 7 and thence around a drum 16 carried by the frame 6. The drum 16 may derive its power from any suitable 95 power plant not here shown. Mounted upon the shaft 12 are L-shaped plates 17 each one of which engages the associated rack 10 and retains its corresponding sprocket 11 in engagement therewith. These plates 17 besides retaining the sprockets 11 in engagement with their racks serve to a more or less extent to retain the shaft 12 and the arm 8 in which it bears at any position to which they may be moved by rotating the 100 power drum 16.

Pivoted to the upright 7 and disposed above the arm 8 is another arm 18 comprising side members corresponding to the side members of the arm 8. Each of the arms 8 and 18 is pivotally connected to a substantially rectilinear framework 19. The frame-

work 19 is provided with suitable sprockets 20 as shown. These sprockets are designed to engage a chain 21 upon which are mounted a plurality of shovels 22. One or more 5 of the sprockets or rather pairs of sprockets, for the sprockets are arranged in pairs in order to engage the parallel links constituting the chain, may derive its power from any suitable driving members not here 10 shown. The framework 19 supports bearings for a drum 23 over which passes a conveyer belt 24. The conveyer belt may be driven by means of power applied to the gear 25.

15 Pivottally carried by the frame 19 is a sub-frame 26, to the lower end of which is pivoted the digger frame most clearly illustrated in Figs. 3 and 4. This digger frame comprises a hollow member 27 pivoted to 20 the frame 26 at 27^a and a beam 28 projecting from the hollow member 27, the hollow member 27 and the beam 28 being provided with pairs of sprocket wheels 29 and 30 as 25 shown. The sprocket wheels 29 and 30 are designed to engage the links of the chain 21 carrying the shovels 22.

Disposed within the hollow member 27 and bearing in bridge members 31 carried by the hollow member 27 is a shaft 32. It 30 should be noted that this shaft is rotatable but is held against longitudinal movement relatively to the hollow member 27. Rigidly mounted upon the shaft 32 is a gear 33 engaged by a worm 34 operated by means of 35 a suitable crank 35 as illustrated. The shaft 32 is provided with a male thread 35 engaging a female thread 36 with which the beam 28 projecting from the free end of the hollow member 27 is provided. It will thus be 40 seen that the beam 28 may be readily adjusted relatively to the hollow member 27 by operating the crank 35. More than one of the cranks 35 and associated worms may be provided if desirable. The hollow member 27 is provided with a plurality of rollers 37 which serve to guide the beam 28 and overcome friction to a great extent.

While the trench digger of my invention 50 is in use the parts are disposed as shown in Fig. 1, the digger frame being adjusted by means of the crank 35 and associated parts.

The operation of the device is so apparent that its operation need not be discussed at length.

55 When the trench digger is to be moved the digger frame may be swung to a horizontal position as shown by dotted lines in Fig. 1. The means here illustrated for raising the digger frame to its horizontal position comprises a drum 38 and a cable 39 which passes 60 over suitable pulleys or rollers as shown and is provided with a hook 39^a adapted to engage the chain carrying the shovels.

As stated before, the precise construction 65 of the vehicle structure is not important as

the digger frame of my invention may be used with a great variety of vehicle structures, it only being important that the vehicle structure be provided with suitable devices for guiding and driving the members carrying the digging shovels and being capable of pivotally supporting the digger frame.

What I claim and desire to secure by Letters Patent of the United States is:

1. In a trench digger, the combination of 75 a vehicle frame, a sub-frame carried by the vehicle frame and devices supported by the vehicle frame for raising and lowering said sub-frame as desired, a digger frame pivoted to the lower end of said sub-frame, said digger frame comprising a hollow member, a second member collapsible within the hollow member, a device for adjusting the second member relatively to the first, sprocket 80 wheels carried by the second member, a chain passing over said sprocket wheels, said chain being provided with digger buckets and other sprocket wheels supported by the vehicle structure and over which said 85 chain passes.

2. In a trench digger, the combination of 90 a vehicle frame, a sub-frame carried by the vehicle frame and devices supported by the vehicle frame for raising and lowering said 95 sub-frame as desired, a digger frame pivoted to the lower end of said sub-frame, said digger frame comprising a hollow member, a second member collapsible within the hollow member, a device for adjusting the second member relatively to the first, sprocket 100 wheels carried by the second member, a chain passing over said sprocket wheels, said chain being provided with digger buckets and other sprocket wheels supported 105 by the vehicle structure and over which said chain passes, said sub-frame comprising a portion arranged to project down over the upper end of the hollow member of the digger frame and so prevent the digger frame 110 from movement under the stress exerted thereon through the chain.

3. In a trench digger, the combination of 115 a vehicle frame, a sub-frame carried by the vehicle frame, devices supported by the vehicle frame for raising and lowering the sub-frame as desired, a digger frame pivoted to said sub-frame, said digger frame comprising a hollow upper member and a lower member collapsible within the upper member, means for adjusting the lower member within the hollow member, sprockets carried by the lower member of the digger frame, sprockets supported by the vehicle 120 frame movable with said sub-frame, a chain 125 carried by said sprockets and buckets on said chain.

4. In a trench digger, the combination of 130 a vehicle frame, a sub-frame carried by the vehicle frame, devices supported by the ve-

hicle frame for raising and lowering the sub-frame as desired, a digger frame pivoted to said sub-frame, said digger frame comprising a hollow upper member and 5 a lower member collapsible within the upper member, means for adjusting the lower member within the hollow member, sprockets carried by the lower member of the digger frame, sprockets supported by 10 the vehicle frame movable with said sub-frame, a chain carried by said sprockets and buckets on said chain, said sub-frame comprising a portion arranged to inclose three sides of the top of the digger frame 15 and so prevent the digger frame from moving under the stress exerted thereon through the chain.

5. A trench digger comprising in combination a vehicle frame, a sub-frame supported by the vehicle frame, devices car- 20

ried by the vehicle frame for adjusting said sub-frame vertically as desired, an extensible digger frame pivoted to said sub-frame, sprockets supported by the vehicle frame vertically adjustable with the sub- 25 frame, sprockets carried by the digger frame and a digger chain mounted upon said sprockets, said sub-frame comprising a portion arranged to prevent movement of the digger frame upon its pivot under the 30 stress exerted upon said digger frame through the digger chain.

In witness whereof, I hereunto subscribe my name this 19th day of March, A. D., 1913.

MICHAEL G. BLICK.
